NAOJIRO YAMANAKA, OF KANAGAWA-KEN, JAPAN

TALKING MACHINE

Application filed January 8, 1930, Serial No. 419,366, and in Japan January 31, 1929.

This invention relates to improvements in talking machines and more particularly to an improved cabinet thereof so constructed that it may provide a relatively large tone 5 chamber of the horn type and has for its object to provide a construction of cabinet to cause the talking machine of small type and especially portable type to reproduce relatively loud and clear sound.

10 In the accompanying drawings:

Fig. 1 is a perspective view of the talking machine.

Fig. 2 is the similar view to Fig. 1, but the top and bottom cover being opened.

15 Fig. 3 is a vertical section on the line III—III of Fig. 2, but the top cover being closed.

Fig. 4 is a cross section on the line IV—IV of Fig. 3.

20 Referring to the drawings, the cabinet is indicated as a whole by the numeral 1, in which a talking machine of well known type may be installed in the usual manner, the tone arm, sound box, turntable and driving 25 motor being indicated by the numerals 2, 3, 4 and 5 respectively.

The cabinet 1 comprises an ordinary hinged top cover 6, a body 7 and a bottom cover 8 swingably connected at 9, 9 to the 30 lower end of the side walls of said body as shown. The body 7 is substantially of a three-sided square box having a special raised bottom 10, the front side-wall being partly omitted, and is provided with a suitable conduit between the lower end of the tone arm 2 and the underside of the raised bottom 10 to form a part of the sound amplifying horn as indicated by the numeral 11 35 by way of example in Figs. 3 and 4. The front part of the raised bottom 10 is upwards curved towards the front end as shown so that it form the sound amplifying horn having the suitably increasing cross sectional area toward the front end.

40 The bottom cover 8 comprises two side walls 12, 12, each having the increasing height towards the front end and adapted to make sliding fit with the corresponding side wall 45 of the body, a bottom wall 13 and a front

wall 14 connected at its lower end to the front end of said bottom wall 13 by means of the hinge 15, which may be suitably curved or flat and carries two wing walls 16, 16 adapted to make sliding fit with the corresponding side wall 12. In closed position, the bottom cover 8 is held in position by any suitable means such as the holding piece 17 co-operating with the slot 18 at the front wall 14 of the bottom cover as shown in Fig. 1. In 55 opened position, the said bottom cover is held positioned by any suitable means such as a screw 19 having a winged thumb piece, the screw being threadable through the side wall 12, into a cavity (not shown) in the body 60 7, whilst the front wall is held opened by any suitable holding means such as the screw 20 adapted to engage the groove 21 on the side walls 12, the side walls 12 and the wing walls 16 being arranged partly to overlap the corresponding side wall of the body and said side wall 11 respectively, so that, as shown in 65 Figs. 2 and 3, these walls combined with the raised bottom form a complete and fir-tight wall of the sound amplifying horn having 70 suitably increasing cross sectional area towards the front open end. The mouth or exit area of the horn can be made quite large, combined with the size of the cabinet. The supports 22 are detachably attached to the body 75 by suitable means such as screw. The arrangement of the front wall 14 with wing walls of the bottom cover may be omitted, if desired. In practical construction, the side walls of the bottom cover can be made so as 80 to make sliding fit with the inside of the side walls of the body, without departing from 85 the scope of the invention.

Having now particularly described and ascertained the nature of my said invention 90 and in what manner the same is to be performed I claim:—

1. In a talking machine, a cabinet comprising a raised bottom of suitable curvature and a bottom cover having two side walls adapted 95 to make sliding fit with corresponding side walls of the body and swingably connected near the rear end of the body so that, when it is swung open, these bottom cover and side walls combined with the raised bottom form 100

a complete and air-tight wall of a part of the sound amplifying horn having suitably increasing cross sectional area towards the front open end of the cabinet.

- 5 2. In a talking machine, a cabinet comprising a raised bottom cover having two side walls adapted to make sliding fit with the corresponding side walls of the body and swingably connected near the rear end of the body and having the front wall, hinged at the front end, with wing walls adapted to make sliding fit with the corresponding walls of the bottom cover, so that, when the bottom cover and the front wall are swung open, these walls
- 10 15 combined with the raised bottom form a complete and air-tight wall of a part of the sound amplifying horn, having suitably increasing cross sectional area towards the front open end of the cabinet.

20 In testimony whereof I affix my signature.
NAOJIRO YAMANAKA.
